United States Patent Office.

JOHN H. CROWELL, OF PROVIDENCE, RHODE ISLAND.

Design No. 2,576, dated February 12, 1867.

DESIGN FOR THE EDGES OF BOOKS.

The Schedule referred to in these Letters Patent and making part of the same.

TO ALL WHOM IT MAY CONCERN:

Be it known that I, JOHN H. CROWELL, of the city and county of Providence, and State of Rhode Island, have originated and designed a new Edge for the Leaves of Books, for sheets of music, pictures, and all leaves to which it may be adapted, of which the following is a full, clear, and exact description, reference being had to the accompanying drawings, making part of this specification.

The leaves of the book, or piece of music, or collection of pictures, or other leaves to which it may be adapted, are to be cut alternately with the curved edges represented in the accompanying drawings, one leaf to present the edge represented by leaf A, and the succeeding or preceding leaf to present the edge represented by leaf B.

The object of this design is to furnish an improved form of device for turning the leaf.

Claim.

What I claim as my invention, and desire to secure by Letters Patent, is—

The design for an improved edge for book and other paper leaves, as herein shown and described.

JOHN H. CROWELL.
